US0D1052008S

(12) **United States Design Patent** (10) **Patent No.:** **US D1,052,008 S**
(45) **Date of Patent:** **** Nov. 19, 2024**

(54) **MODEL VEHICLE WINDOW ASSEMBLY**

(71) Applicant: **TRAXXAS, L.P.**, McKinney, TX (US)

(72) Inventors: **Adam Cole Ewing**, McKinney, TX (US); **Otto Karl Allmendinger**, Rowlett, TX (US); **Kent Poteet**, Lucas, TX (US); **Jaime Felix Barajas**, Dallas, TX (US); **Ross Martin**, Roanoke, TX (US); **Trent Collins**, McKinney, TX (US); **Caleb Hix**, McKinney, TX (US)

(73) Assignee: **TRAXXAS, L.P.**, McKinney, TX (US)

(**) Term: **15 Years**

(21) Appl. No.: **29/852,416**

(22) Filed: **Sep. 7, 2022**

(51) LOC (14) Cl. **21-01**

(52) U.S. Cl.

USPC **D21/562**; D21/561

(58) **Field of Classification Search**

USPC D21/424, 433, 434, 483, 495, 533, 548, D21/552, 558, 561, 562, 565, 581; D12/82, 86, 90, 91, 93, 114, 163, 164, D12/167, 172, 181, 182, 196, 401, 406

CPC A63H 17/00; A63H 17/004; A63H 17/002; A63H 33/26

(57) **CLAIM**

The ornamental design for a model vehicle window assembly as shown and described.

DESCRIPTION

FIG. 1 is an upper, left, front perspective view of a model vehicle window assembly showing our new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is an upper plan view thereof;

FIG. 7 is a lower plan view thereof;

FIG. 8 is an upper, right, rear perspective view thereof; and, FIG. 9 is a lower, right, rear perspective view of the model vehicle window assembly.

In the drawings, the broken lines illustrate portions of the model vehicle window assembly that form no part of the claimed design.
